(57) CLAIM

The ornamental design for an inflatable aircraft bed and carrying case assembly, as shown and described.

DESCRIPTION

FIG. 1 is a top perspective view of the unassembled aircraft bed part of the inflatable aircraft bed and carrying case assembly.

FIG. 2 is a top perspective exploded view of the air bladder part thereof.

FIG. 3 is a bottom perspective view thereof.

FIG. 4 is a top perspective view of the air bladder part of the inflatable aircraft bed and carrying case assembly.

FIG. 5 is a bottom perspective view thereof.

FIG. 6 is an enlarged detail view of the seat belt opening area 6 circumscribed within FIG. 4.

FIG. 7 is an enlarged detail view of area 7 circumscribed within FIG. 5.

FIG. 8 is a bottom perspective view of the mattress part of the inflatable aircraft bed and carrying case assembly.

FIG. 9 is a top perspective view thereof.

FIG. 10 is an enlarged detail view of the zipper start on area 10 circumscribed within FIG. 8.

FIG. 11 is the top perspective view of the assembled aircraft bed of the inflatable aircraft bed and carrying case assembly.

FIG. 12 is a top perspective view of the unassembled inflatable aircraft bed and carrying case assembly.

FIG. 13 is a top perspective view of the carrying case including the mattress part.

FIG. 14 is an enlarged detail view of the area 14 circumscribed within FIG. 12.

FIG. 15 is an enlarged detail view of the area 15 circumscribed within FIG. 12; and,

FIG. 16 is top and rear perspective view of the carrying case part of the inflatable aircraft bed and carrying case assembly. The evenly spaced broken lines immediately adjacent and parallel to the edges of the article depict the claimed welding seams of the article. All other evenly spaced broken lines depict features of the inflatable aircraft bed and carrying case assembly that form no part of the claimed design. The dash dot dash broken lines denote the boundaries of the

detail areas and the directional lines of assemblage and form
no part of the claimed design.
